CLAIM

The ornamental design for a laptop computer, as shown and described.

DESCRIPTION

FIG. 1 is a front, right side perspective view of a laptop computer having its display housing opened;

FIG. 2 is a rear, left side perspective view thereof;

FIG. 3 is a front elevational view thereof;

FIG. 4 is a top view thereof;

FIG. 5 is a left side elevational view thereof;

FIG. 6 is a right side elevational view thereof;

FIG. 7 is a rear elevational view thereof;

FIG. 8 is a bottom view thereof;

FIG. 9 is a front, right side perspective view of the laptop computer having its display housing closed; and,

FIG. 10 is a front, right side perspective view of the laptop computer having its display housing closed and handle extended.

The broken lines are shown in the views for illustrative purposes only and form no part of the claimed design.
